C. REYNOLDS

HUMIDOR

Filed May 5, 1924

Inventor

Charles Reynolds
By
Cyrus N. Lee

Attorney

UNITED STATES PATENT OFFICE.

CHARLES REYNOLDS, OF NASHVILLE, TENNESSEE, ASSIGNOR TO ELYMA REYNOLDS.

HUMIDOR.

Application filed May 3, 1924. Serial No. 710,915.

To all whom it may concern:

Be it known that I, CHARLES REYNOLDS, a citizen of the United States, residing at Nashville, in the county of Davidson and State of Tennessee, have invented a new and useful Improvement in Humidors, of which the following is a specification, reference being had to the accompanying drawing.

10 My improvement relates particularly to apparatus to be used for humidifying the air in compartments containing commodities which deteriorate through becoming excessively dry. As examples of such compartments, reference is made to compartments or cases containing cigars and similar tobacco products.

15 The object of my invention is to produce such an apparatus in a form which may be economically manufactured and which is in form convenient for handling and operation.

20 The accompanying drawing is a sectional elevation of an apparatus embodying my invention.

25 Referring to said drawing, A is an upright receptacle or tank of glass or porcelain or metal or any other material adapted to make said receptacle fit to hold 30 water. Said receptacle has at its upper end an upward-directed open neck, A¹, the interior of which is preferably circular or cylindrical and slightly tapering from its upper edge downward, as shown.

35 Said neck receives the lower end of the upper structure or cap which comprises the upright, approximately cylindrical wall, B, and the upper cross wall or top, B¹. The lower end of the wall, B, is slightly tapering to conform to the taper of the interior 40 of the neck, A¹. At the middle of the cross wall or top, B¹, is an opening into which is fitted an incandescent electric lamp socket, C.

45 For the sake of convenience in manufacture, the upper structure or cap is preferably made of sheet metal, the metal around said opening being flared upward and a collar, B², being applied to the under face 50 of the top and around said opening, said collar and the flared part of the top together forming a cylindrical chamber having an extended area for engagement with the socket, C. The socket is placed into 55 position in said collar while the cap, C¹,

and the key, C², and the conductor cords, C³, have been detached.

Above the neck, A¹, of the tank, the cap is provided with apertures, B³, for the escape of vapor from the tank. The drawing shows such openings in the wall, B, and also in the top, B¹.

The lamp, D, extends from the socket, C, downward into the tank. Any desired quantity of water is to be placed into the tank. The water may extend to the neck, A¹, as shown by the drawing, and the lamp, D, may be long enough to cause its lower end to reach into the water, whereby the water will make direct contact with the lamp to be heated by the lamp. However, if so desired, the lamp may be short and the water may be lower, whereby the water will not make contact with the lamp, but will receive heat by radiation from the lamp.

The bottom of the tank, A, forms a base for the apparatus, and the apparatus is to be set into the compartment which is to be humidified, the apparatus resting on said base. When the apparatus has been thus placed, the electric current is delivered to the lamp through the cords, C³, whereby the lamp is heated. By means of such heating, the water in the tank is warmed or heated sufficiently to cause evaporation. The vapor thus produced passes outward through the apertures, B³, and is distributed throughout the compartment in which the apparatus is located.

Attention is especially invited to the fact that this apparatus may be easily and economically manufactured. The tank, A, is of a form adapted to easy manufacture in a single piece of glass or porcelain or metal, and without adding or attaching any parts. The cap is also easy to manufacture. No working parts are made a part of the cap. The lower part of the cap is made to fit the interior of the upper part of the neck, A¹, and make such frictional engagement as will hold the cap in position. No latch or other holding mechanism need be used. The lower part of the cap may fit into the neck, A¹, so closely as to prevent the passing of vapor and also to prevent the passing of water while the apparatus is being handled, whereby no water may escape from the apparatus at any point below the apertures, B³.

At the same time, the cap may be readily removed for the introduction of more water into the tank or to inspect or replace the lamp, or for any other purpose. And the 5 lamp and the cap may be replaced on the tank by merely moving the lamp and cap downward from above the tank and allowing the lower part of the wall, B, to enter the neck, A⁴.

10 The removal and replacing of the cap and the lamp may be effected without disturbing the tank, A. In practice, the empty tank may be set on the floor of the compartment or case in which it is to operate, and water 15 then poured into the tank, and the cap and lamp then put into position on the neck, A⁴, of the tank. If so much of the water is evaporated from the tank as to call for replenishing, the cap may be lifted away 20 from the tank, without disturbing the tank, and more water then poured into the tank, and the cap and lamp then replaced by entering the lower part of the cap into the neck, A⁴.

25 It is to be understood that the tank may be of any desired material, size and shape; the size depending in part upon the size of the compartment in which the apparatus is to be used.

30 I claim as my invention:

35 1. In an apparatus of the kind described, the combination of an upright tank having at its upper end an upward-directed open neck, a cap adapted to engage said neck, one of said members being apertured for the escape of vapor, an upright lamp socket in said cap, and an upright lamp extending downward from said socket, substantially as described.

40 2. In an apparatus of the kind described, the combination of an upright tank having at its upper end an upward-directed open neck, a cap adapted to fit into said neck, one of said members being apertured for 45 the escape of vapor, an upright lamp socket in said cap, and an upright lamp extending downward from said socket, substantially as described.

50 3. In an apparatus of the kind described, the combination of an upright tank having at its upper end an upward-directed cylindrical open neck, a cylindrical cap adapted to engage said neck, one of said members being apertured for the escape of vapor, an 55 upright lamp socket in said cap, and an upright lamp extending downward from said socket, substantially as described.

60 4. In an apparatus of the kind described, the combination of an upright tank having at its upper end an upward-directed open neck, a cap centrally open and having an upright wall adapted to engage said neck and extend above said neck, one of said

members being apertured for the escape of vapor, an upright lamp socket located centrally in said cap, and an upright lamp extending downward from said socket, substantially as described. 65

5. In an apparatus of the kind described, the combination of an upright tank having at its upper end an upward-directed open neck, an apertured cap centrally open and having an upright wall adapted to engage said neck and extend above said neck, an upright lamp socket in said cap, and an upright lamp extending downward from said socket, substantially as described. 70

6. In an apparatus of the kind described, the combination of an upright tank having at its upper end an upward-directed open neck, an apertured tapering cap adapted to fit into said neck, an upright lamp socket in said cap, and an upright lamp extending downward from said socket, substantially as described. 75

80 7. In an apparatus of the kind described, the combination of an upright tank having at its upper end an upward-directed cylindrical open neck, an apertured cylindrical tapering cap adapted to engage said neck, an upright lamp socket in said cap, and an upright lamp extending downward from said socket, substantially as described. 85

8. In an apparatus of the kind described, the combination of an upright tank having at its upper end an upward-directed open neck, a cap having an upright apertured wall adapted to engage said neck, an upright lamp socket located centrally in said cap, and an upright lamp extending downward from said socket, substantially as described. 90

9. In an apparatus of the kind described, the combination of an upright tank having at its upper end an upward-directed cylindrical neck, a cap having an upright apertured tapering wall adapted to fit into said neck, an upright lamp socket located centrally in said cap, and an upright lamp extending downward from said socket, substantially as described. 100

10. In an apparatus of the kind described, the combination of an upright tank having at its upper end an upward-directed open neck, an apertured cap adapted to loosely engage said neck and having a tubular collar, an upright lamp socket in said cap, and an upright lamp extending downward from said socket, substantially as described. 115

110 In testimony whereof I have signed my name, this 26th day of April, in the year one thousand nine hundred and twenty-four.

CHARLES REYNOLDS.
